DEVICE FOR AND METHOD OF SETTING
SPARK PLUG ELECTRODES

Lewis M. Oden, Sr., Ocean View, Va.

Application August 31, 1944, Serial No. 552,113

22 Claims. (Cl. 153—48)

(Granted under the act of March 3, 1883, as
amended April 30, 1928; 370 O. G. 757)

This invention relates to devices for and a method of adjusting the gap between the central and outer electrodes of spark plugs.

The operation of adjusting the gap between the electrodes of a spark plug is ordinarily a time consuming and tedious operation when done by the commonly practiced methods. Frequently, the gap is made too small, and in the resulting attempt to separate the electrodes a bending moment is exerted on the central electrode which will fracture the porcelain, thus ruining the spark plug.

It is the major object of my invention to provide a machine which will accurately set the gap between the electrodes in a quick operation, in such a manner that the central electrode will not be strained.

It is another important object of my invention to provide a spark plug gapping machine wherein at least two outer electrodes can be accurately and simultaneously positioned with respect to the central electrode.

Another object of the invention is to provide a spark plug gapping machine which is simple and fool proof in operation whereby an unskilled person can be taught to operate it with a minimum of instruction and practice.

Other objects will be apparent as the description proceeds in connection with the drawings, in which:

Fig. 1 is a side view of one embodiment of the machine;

Fig. 2 is a front view of the machine shown in Fig. 1;

Fig. 3 is a partial vertical sectional view along the line 3—3 of Fig. 2, looking in the direction of the arrows;

Fig. 4 is a sectional view along the line 4—4 of Fig. 1, looking in the direction of the arrows;

Fig. 5 is an enlarged partial sectional view showing a gapping operation on a spark plug;

Fig. 6 is an enlarged partial sectional view showing a gapping operation on another type of spark plug, using a modified gapping head;

Fig. 7 is a sectional view through the gapping head of Fig. 5, along the line 7—7 of Fig. 5 and looking in the direction of the arrows;

Fig. 8 is an enlarged pictorial view of one of the feelers used in the embodiment of Fig. 5;

Fig. 9 is an enlarged pictorial view of an adjustor member as used in Figs. 1 to 5 and 7;

Fig. 10 is an enlarged pictorial view of the adjustor member used in the embodiment of Fig. 6;

Fig. 11 is an enlarged pictorial view of one of the feelers used in the embodiment of Fig. 6;

Fig. 12 is a pictorial view of a bent hold down plate used particularly with the gapping head shown in Fig. 6; and

Fig. 13 is a view of a part of Fig. 3, showing a modification.

As shown in Figs. 1 and 3, the machine comprises a frame or arbor casting 10 which has opposing upper and lower jaw portions 11 and 12, and a flat base 13 with bosses 14 and 15 which are bored to receive bolts 16 or the like for fastening the machine to a support.

The upper jaw 11 has two parallel bores 18 and 19 (Fig. 3) perpendicular to the jaws 11 and 12. A rack 20 has a sliding fit in bore 18 and is moved up and down in the bore by means of a pinion 21 which is journaled in the jaw 11 and engages the teeth on the rack. An operating handle 22 is fixed to the pinion shaft 23 to rotate it in operating the rack.

20 The rack 20 has a central bore 25, the lower end of the bore accommodating with a sliding fit a stud 26 which projects upwardly from a gapping head 27. A coiled compression spring 28 is located within the bore 25, with its bottom end 25 on top of the stud 26 and its upper end against an internal shoulder 29 where the diameter of the bore 25 is reduced. A bolt 30 fits in the reduced bore 31 and extends through the spring 28. The head of the bolt engages the top of the rack 20 and its threaded lower end has engagement with the threads in a tapped hole in the stud 26. Thus the spring 28 is compressed between the shoulder 29 and the top of the stud 26 and the head of the bolt 30 is held against the top of the rack 20. The axial position of the stud 26 in the bore 25 is adjusted by turning the bolt 30 by its head.

Adjacent its upper end the rack 20 is reduced in diameter to provide a shoulder 33. A cross-piece or yoke 34 has a bore therethrough which has a press fit over the reduced portion of the rack and seats against the shoulder 33. A tapered pin 35 passes through both the yoke and the rack to fix them in their relative positions. A bushing 36 having a central bore 37 is threaded through the yoke adjacent its other end.

Passing through the central bore 37 in the bushing is a push-rod 38, there being means such as set-screws 39 to fix the axial position of the push-rod in the bore. At its upper end the push-rod has a handle or knob 42 threaded thereon, by which means the push-rod is positioned in the bore 37 when the set-screws 39 are loosened. At its lower end the push-rod is threaded into the upper part of a wedge 43, the wedge and the bot-

tom part of the push-rod passing through the bore 19 in the upper jaw portion 11. The wedge is in two parts hinged together by a pin 44 so that its pointed lower part is free to move from left to right when viewed from the front as in Fig. 5. The lower part of the push-rod is guided by a bushing 45 which seats on top of the upper jaw portion 11 and within the bore 19.

The upper surface of the bushing 45 provides a seat for a compression spring 46 which surrounds the push-rod 38 and extends between the jaw 11 and the underside of the yoke 34, there being a washer 47 between the top of the spring and the yoke, having a recess to locate upper end of the spring properly about the push-rod. The spring 46 aids the lifting of the push-rod, yoke, and rack back to their uppermost position after they have been lowered by the pinion 21 during a gapping operation and is strong enough to keep these parts in their uppermost position when no downward force is applied to the handle 22.

A support 50 which may be a casting having a substantially U-shaped or channel-like cross-section as shown in Fig. 3, is fastened to the upper side of the lower jaw 12 by bolts 51 or the like. The channel of the support extends transversely of the jaw, thus defining forward and rear legs 52 and 53. A pair of oppositely disposed jaws 54 and 55 (Figs. 2 and 4) are pivotally mounted on top of the forward leg 52 by means of screws or the like 56 and 57 respectively. A yoke 58 overlies the pivoted jaws, the screws 56 and 57 passing through the yoke with their heads on top of the yoke. At their rear ends the jaws overlie the rear leg 53 of the support 50 and are pivotally connected to a pair of cam followers 62 and 63 respectively by pivot screws 64 and 65. The cam followers slide on the top surface of the rear leg 53 which is in substantially the same plane as the top surface of the front leg 52. At their inner and adjacent ends the cam followers 62 and 63 are provided with rollers 66 and 67 respectively which rotate about axes parallel to the top surface of the leg 53, the rollers being engaged by the opposite inclined faces of the wedge 43. A groove or track 68 is provided in the top surface of the rear leg 53, the rollers 66 and 67 being restrained from sideways movement by the walls of the groove, as shown in Fig. 3.

As shown in Fig. 4 a tensioned coil spring 69 is connected to the jaws by eye-bolts 70 and 71 to spread the opposed jaws apart and to urge the cam followers 62 and 63 together, so that the rollers 66 and 67 are resiliently held against the inclined faces of the wedge. A guide plate 74 is fixed to the back of the rear leg 53 in any desired manner, the back face of the wedge 43 resting thereagainst and being guided thereby between the rollers 66 and 67. Set-screws 75 and 76 (Fig. 4) are adjustable in lugs attached to the rear leg 53 to engage the inner ends of the jaws 54 and 55 and limit their inward travel, there being lock nuts on the set-screws to tighten them in their adjusted positions.

From the above description it is seen that when the pinion 21 is rotated to lower the rock 20 and push-rod 38, the wedge 43 is moved downward toward the rear leg 53 of the support 50, its opposed inclined faces engaging the rollers 66 and 67 and moving the jaws about their pivots 56 and 57 against the tension of the spring 69 so that their outer ends move towards each other. When the rack, push-rod, and wedge are moved

upward the outer ends of the jaws 54 and 55 separate due to the action of spring 69.

The lower jaw portion 12 of the frame 10 projects farther forward than the upper jaw 11 to provide a projecting support 77. This support 77 has a recess 78 as best shown in Figs. 2, 3 and 4. A plate 79 having a recess aligned with the recess 78 is fastened to the top of the projecting support 77 by screws 80 and 81. The support 77 with the plate 79 form a base onto which an adaptor 84 can be slid through the open end of the recess 78. As best shown in Figs. 3 to 6 the adaptor has a loose fit within the recess so that it can be shifted in the plane of the plate 79; there being a radial flange 85 which overlies the edges of the plate to support the adaptor. The front wall of the forward leg 52 is recessed at 86 to prevent interference with the radial flange 85.

The adaptor has a central bore with an inwardly extending radial flange 82 to support a spark plug as shown in Figs. 3, 5 and 6. It is intended that the spark plug fit loosely in the adaptor and the adaptor fit loosely in the recess 78 so that the spark plug can be easily shifted and aligned with the gapping head 27 before the gapping operation is begun.

In Fig. 5 is shown an enlarged view of the gapping head during a gapping operation. A spark plug 87 is seated in the adaptor 84 which has been slid into the recess and is resting on the plate 79. A second ring adaptor 88 within adaptor 84 may be used to raise the spark plug to the proper height for engagement with the gapping head. Several of the adaptors 84 and 88 are furnished with the machine to accommodate spark plugs of various dimensions. The gapping head 27 has a body portion 89 having an offset to the right as viewed in Fig. 3 and from which the stud 26 extends. As shown in Figs 3, 4 and 7, the forward face of the body portion has a vertical slot 90 extending from top to bottom. An adjustor member 91 (Figs. 3, 7 and 9) is T-shaped in cross-section for the lower half of its length, its central leg 92 sliding in the slot 90. The upper half of its length does not have the central leg 92. At its top portion 93 the central leg has a sliding fit in the slot 90, the rest of the central leg being narrower, the narrow portion terminating at shoulders 94 and 95 (Fig. 9). The narrow portion of the central leg below the shoulders 94 and 95 is to provide space for oppositely disposed and similar feelers 96 and 97, one on each side of the leg. The feeler 96 is shown pictorially in Fig. 8. As shown it has a wide flat portion 98 at the top, and a narrower flat lower portion 99 of substantial length which terminates in a bottom portion 100 which is so shaped as to mate with the periphery of the central electrode 101 of the spark plug as shown in Fig. 5. The thickness of the two feelers 96 and 97 plus that of the central leg 92 of the adjustor 91 below the shoulders 94 and 95 are such that when assembled the adjustor and the feelers may slide in the slot 90. The tops of the wide flat portions 98 of the feelers bear against the shoulders 94 and 95 so that the upward movement of the feelers in the slot 90 is limited by their engagement with the adjustor in this manner. Thus the vertical position of the adjustor 91 determines the vertical position of the feelers within slot 90.

The width of the wide flat portions 98 of the feelers is slightly greater than the depth of the slot 90 so that as shown in Fig. 7 these wide portions project slightly beyond the forward face of the body portion 89, and the cross-piece 101 of

the adjustor 91 is therefore slightly spaced from the said forward face. A plate 101 covers the front of the body portion 89 of the gapping head 27, being clamped thereto by four screws 102 to 105. The plate 101 has a vertical groove 106 slightly deeper than the thickness of the cross-piece 107 of the adjustor member 91 so that the adjustor member and the feelers are not clamped against movement by the plate 101. A set-screw 109 is threaded through the plate 101 as shown in Figs. 3 and 7 and engages the front of the cross-piece. When the set-screw 109 is tightened against the adjustor 91 the feelers 96 and 97 are clamped between the bottom of the slot 90 and the cross-piece of the adjustor member, as shown most clearly in Fig. 7.

Means are provided to shift the adjustor 91 vertically within the slot 90 when the set-screw 109 is loosened. Shifting the adjustor provides vertical adjustment of the feelers 96 and 97. A disc 110 (Figs. 3, 4 and 5) is rotatably seated in the forward face of the body portion 89, the disc being wider than the width of the slot 90. A stud 111 projects from the front face of the disc 110, but offset from the axis of the disc. The stud projects through a horizontal slot 112 in the cross-piece 107 and has a screw driver slot by which the disc can be rotated. When the set-screw 109 is loosened, rotation of the stud 111 and disc 110 causes a raising or lowering of the adjustor member due to the engagement of the offset stud in the slot 112. In the embodiment of Fig. 5, using the member 91 of Fig. 9, when raising the adjustor member as described, the operator must be certain that the feelers are pushed upward against the shoulders 94 and 95.

Integral with the body portion 89 of the gapping head 27 are a pair of arms 115 and 116 extending at right angles thereto as shown in Figs. 2 to 5. Each arm has two coaxial bores (Fig. 5) extending therethrough, the outer bores 117 and 118 being larger in diameter than the inner bores 119 and 120, there being shoulders 121 and 122 at their juncture. Similar rams 126 and 127 are disposed for sliding movement in the bores, the rams having portions of large and small diameter to fit the corresponding bores in the arms 115 and 116, and there being shoulders on the rams where their diameter changes. Similar coiled compression springs 128 and 129 surround the small portions of the rams and are compressed between the aforesaid shoulders on the rams and the shoulders 121 and 122, the action of the springs being to urge the rams outward and away from each other. Rotation of the rams in the bores is prevented by screws 132 and 133 which are threaded through the walls of the arms and slidably engage longitudinal slots 134 and 135 in the rams. The screws 132 and 133 also limit the axial movement of the rams when they engage the ends of the slots.

At their inner ends the faces of the rams are inclined to substantially the same angle as the outer electrodes of the spark plug which is being gapped, as shown in Fig. 5. As also shown in Fig. 5, the underside of the rams are recessed at 136 for a portion of their length to avoid interference with the movement of the ram by the threaded portion of the spark plug.

In ordinary use a large number of identical spark plugs are gapped at one time. If a different lot of another type of plug is to be gapped, the rams shown can be replaced by others having their inner ends properly tapered, and the recesses 136 properly located so as to accommodate

the plugs of this lot. In a similar manner the adaptor 84 and adaptor ring 88 may be changed to accommodate the plugs of the new lot.

The action of the gapping head 27 during a gapping operation is as follows: After the spark plug 67 has been mounted in its adaptor and is in position to be gapped, the gapping head is lowered by rotating the handle 22 and the pinion 21. The gapping head is lowered with the rack even though slidably mounted in the bore of the rack, because of the compression of the spring 23. While the gapping head is being lowered the operator guides the bottom portions 100 of the opposed feelers 96 and 97 into the gaps between the central electrode and a pair of opposite outer electrodes, as illustrated in Fig. 5. The operator may shift or rotate the spark plug and its adaptor in the plane of the plate 79 to obtain proper alignment of the spark plug and the feelers while lowering the gapping head. A pair of vertically adjustable studs 149 and 150 which are threaded into the support 77 engage the bottom of the arms 115 and 116, when the gapping head 27 has moved downward to the desired position for gapping, as shown in Fig. 5. Further downward movement of the gapping head is thus prevented.

As rotation of the pinion is continued, the rack 20, yoke 34, push-rod 38 and the wedge 43 continue their downward movement. However, since the gapping head 27 cannot move further due to engagement of the arms 115 and 116 with the studs 149 and 150, the stud 26 will slide in the central bore 25 and further compress the spring 23 against the shoulder 33. With the continued downward movement of the rack 20 the opposed inclined portions of the bottom of the wedge engage the rollers 66 and 67 to separate the cam followers 62 and 63 and rotate the jaws 54 and 55 so that their outer ends move towards each other as previously described. During this period, before the rams 126 and 127 engage the outer electrodes of the spark plug, the operator may shift the plug and its adaptors 84 etc. to properly align the plug with the feelers and rams.

As the outer ends of the jaws move towards each other they engage the outer ends of the rams 126 and 127 and force them towards each other until they engage the outer electrodes of the spark plug. With continued movement of the rams the opposite electrodes are both forced toward the central electrode until they are stopped by the feelers 96 and 97 which are clamped between the central and outer electrodes. Fig. 5 shows the apparatus in this condition, the outer electrodes being forced against the feelers which separate them from the central electrode. Fig. 5 thus illustrates the completion of the gapping operation on a pair of opposite outer electrodes except for the remaining operation of withdrawing the rams and feelers from engagement with the spark plug. Since the material of the spark plug electrodes is somewhat resilient, the outer electrodes will spring back slightly when the rams are withdrawn. For this reason the feelers 96 and 97 are a little thinner than the gap which is desired between the central and outer electrodes, so that when the outer electrodes spring back to their final position the final gap between the central and outer electrodes will be the correct desired gap.

When the handle 22 is moved upward it will release the rams and lift the feelers from the gap between the electrodes. However, since the feelers will be slightly bent at their bottom as shown in Fig. 5, the lifting of the feelers will normally

lift the spark plug too since the feelers do not lift easily from the gaps. In order to keep the spark plug from being lifted in this manner, a stop plate 140 (Figs. 1, 3 and 4) is fastened to the top of leg 52 by screws 141. As shown in Fig. 4, the stop plate 140 extends forward and overlies the rear of the threaded portion of the spark plug which is shown in dotted lines in Fig. 4. The stop plate holds the spark plug down and thus the feelers are withdrawn from the gap when the handle 22 is raised. The plate 140 is just slightly above the spark plug so that it does not engage the plug when the plug is inserted under the gapping head or withdrawn after the gapping operation.

The withdrawal of the rams from the spark plug is automatic when the operator raises the handle 22, due to the action of the spring 69 which separates the jaws 54 and 55, and to the springs 128 and 129 which act to return the rams to their outer positions. The vertical range of movement of the gapping head is less than that of the rack because of the sliding action of the stud 23 as previously described, and in fact the limits of vertical movement of the head are such that the outer ends of the rams 126 and 127 will always be engaged with a portion of the outer ends of the jaws 54 and 55, this engagement resulting from the action of the springs 128 and 129.

In practice the adjustments provided by bolt 30 in the stud 26; by the engagement of set-screws 39 with the push-rod 38; by disc 110 and stud 111; by the use of different adaptors 84 and ring adaptors 88; by the adjustment of studs 149 and 150; and by screws 75 and 76 allow the machine to be adjusted to operate on spark plugs of a wide variety of sizes; the time spent in adjusting the machine when changing from a lot of plugs of one size to a lot of another size being inconsequential as compared to the rapidity with which the remaining plugs of the lot can be properly and accurately gapped.

The gapping operation described above, and illustrated in Fig. 5, simultaneously gaps the two opposite outer electrodes on a spark plug having outer electrodes diametrically opposite to each other. If the plug has four equally spaced outer electrodes it must be rotated 90 degrees after the first two opposed electrodes are gapped, so that the remaining two electrodes are in position for gapping. If the plug has six equally spaced outer electrodes a third operation is necessary, and so forth.

Because of the construction of the apparatus whereby the spark plug can be shifted into exact proper alignment with the feelers and rams before pressure is exerted by the rams, the force applied to the outer electrodes by the rams does not impose any bending strain upon the central electrode. Due to the pivoted connection 44 between the wedge 43 and the push-rod 38, each ram exerts a force equal to and opposite to that of the opposed ram, and during the gapping operation the outer electrodes are bent towards each other until they are stopped when the feelers and the central electrode become clamped between the outer electrodes as shown in Fig. 5. The material of the feelers 96 and 97 is sufficiently flexible so that they can be pulled out from the gap without disturbing the gap setting. This flexibility is necessary when the contour of the gap flares as shown in Fig. 5 since as is clear from that figure the outwardly flared bottom portions 100 of the feelers must be squeezed towards each other as they are pulled upward out of the gap.

The gapping head shown in Fig. 5 is particularly

adapted for operations on spark plugs wherein the end of the central electrode is substantially cylindrical so that the thrust of the rams is most effective when perpendicular to the axis of the electrode. The gapping head of Fig. 6, however, is designed particularly for spark plugs having a conically tapered central electrode as in the type shown mounted in the adaptor 84 in Fig. 6. The arms 156 and 157 and the rams 158 and 159 therein are substantially perpendicular to the surface of the conical central electrode instead of perpendicular to its axis as in the embodiment of Fig. 5. The faces of the outer ends of the rams are parallel to the faces of the jaws 54 and 55 and the action of the gapping head shown in Fig. 6 is exactly the same as that of Fig. 5 except for the direction of the force exerted by the rams.

The adjustor member 160 used in the gapping head of Fig. 6 is slightly different from that used by the head of Fig. 5. Fig. 10 shows the adjustor member 160 used in Fig. 6, which differs from that shown in Fig. 9 by the provision of opposite grooves 161 and 162 just under the wide top portion of the central leg 164 of the adjustor member.

One of the feelers 165 and 166 used in the gapping head of Fig. 6 is shown in Fig. 11. As appears in Fig. 11 the feeler 166 has a lip 167 at right angles to the plane of the main body of the feeler and at the top of the wide flat portion 168, the lip being of such size as to fit into the groove 161 of the adjustor member 160. The lip 167 and groove 161 have the purpose of causing the feeler to move with the adjustor member when the adjustor member is raised by the rotation of stud 139, and also the function of preventing the feeler from being pulled out of the gapping head when the gapping head is being raised and the feeler is being pulled out of the gap between the inner and outer electrodes after a gapping operation. This feature is more necessary when gapping a spark plug of the type shown in Fig. 6 because it is more difficult to withdraw the feeler from the gap than from the spark plug of Fig. 5, but it is to be understood that this feature of the lip on the feeler engaging a slot in the adjustor member is also advantageous when using a gapping head of the type of Fig. 5 because the feelers are then raised and lowered with the adjustor member when the position of that element is being adjusted. The width of the wide flat portion 168 of the feeler is such as to allow the feeler to be clamped in the gapping head by the adjustor member by tightening the set-screw 172 in the same manner as when screw 109 is tightened in Fig. 5.

The lower end 173 of the feeler 166 is flared slightly outwardly as shown in Fig. 11 so that it will have a shape and inclination more closely approximating its final inclination during a gapping operation as shown in Fig. 6. Because of this flare, the lower end is advantageously inserted into the gap between the inner and outer electrodes by moving it sideways through the gap between adjacent outer electrodes. While only one feeler 166 is shown in detail in Fig. 11 it is to be understood that the opposite feeler 165 is identical thereto except for the reversal of the directions in which the lip and inclined lower end extend.

Because of the different dimensions of the gapping head of Fig. 6, the spark plug is held a little lower than in Fig. 5. For that reason the stop plate 142 of Fig. 12 is substituted for the stop plate 140 when using the gapping head of Fig. 6, since stop plate 140 would be too far above

the spark plug to hold it in the intended manner when removing the feelers.

In the modification shown in Fig. 13, the stop plate 140 has a tapped hole adjacent its forward end, to accommodate a machine screw 180 having an enlarged head 181. The screw is vertically adjustable in the stop plate, having means such as a hole through its head through which a pin can be inserted to turn it, and underlies the body portion 89 of the gapping head as shown. The screw 180 may be used instead of the two studs 149 and 150 because it limits the downward movement of the gapping head when adjusted to the proper height. It will be seen from Fig. 13 that the body portion 89 will be stopped during its downward movement by the screw 180.

When using the gapping head of Fig. 6 the stop plate 142 may be provided with a screw 180 in the same manner as plate 140 is provided therewith in Fig. 13, and the action will be the same as with the screw in plate 140. If desired, instead of using the stop plate 142 with the gapping head of Fig. 6, the straight stop plate 140 may be used. When this is done, the screw 180 is reversed in the plate so that its head 181 is below the plate. The head 181 is large enough in diameter so that it will project over the base of the spark plug and hold it down when the feelers are withdrawn, in the same manner that the stop plate 142 does when used. When so used, the threaded end of the screw projects upwards through the plate and stops the downward movement of the gapping head.

Thus when using the screw 180 instead of the studs 149 and 150 it is possible to eliminate the studs 149 and 150 and the stop plate 142 of Fig. 12.

It will be understood that the above description and accompanying drawings comprehend only the general and preferred embodiment of the invention and that various changes in details of construction, proportion and arrangements of parts may be made within the scope of the appended claims and without sacrificing any of the advantages of the invention.

The invention described herein may be manufactured and used by or for the Government of the United States of America for governmental purposes without the payment of any royalties thereon or therefor.

What is claimed is:

1. A device for adjusting the gap in spark plugs comprising at least two equiangularly spaced feelers mounted on said device and adapted to be inserted between the central and outer electrodes of a spark plug; means operable to simultaneously press the outer electrodes towards the central electrode with said feelers clamped therebetween, the forces exerted by said means against the central electrode forming a closed force diagram without the imposition of any bending moment upon the central electrode; and actuating means on said device operable to first insert said feelers into the gaps and then to actuate said means.

2. A device for adjusting the gap in spark plugs comprising at least two equiangularly spaced feelers mounted on said device and adapted to be inserted between the central and outer electrodes of a spark plug; first means operable to insert said feelers into the gaps between said electrodes; second means operable to simultaneously press the outer electrodes towards the central electrode until said feelers are clamped therebetween, the forces exerted by said second means against the central electrode forming a closed force diagram without the imposition of any bending moment

upon the central electrode; said first means being operable to actuate said second means after the insertion of said feelers has been completed.

3. The apparatus described in claim 2 wherein the forces exerted by said second means, and consequently the force diagram thereof, lie substantially in a plane perpendicular to the axis of the central electrode of the spark plug.

4. The apparatus described in claim 2 wherein the forces exerted by said second means do not lie in the same plane, and their resultant is opposed by a force along the axis of the spark plug central electrode.

5. A device for adjusting the gap in spark plugs comprising a support adapted to support a spark plug so that it is freely shiftable in a plane perpendicular to the axis of its central electrode; at least two feelers mounted on said device and adapted to be inserted between the central and outer electrodes of the spark plug; first means operable to insert said feelers into the gaps between said electrodes; second means operable to simultaneously press the outer electrodes towards the central electrode until said feelers are clamped therebetween, said second means being so constructed and arranged that the forces exerted by said second means against the central electrode form a closed force diagram without the imposition of any bending moment upon the central electrode; said first means being operable to actuate said second means after the insertion of said feelers has been completed, and said support permitting the shifting of the spark plug during the operation of said second means.

6. The device described in claim 5 wherein said first means is operable to pull said feelers from the gap between the electrodes; and stop plate means operable to hold the plug during the removal of said feelers.

7. A device for adjusting the gap in spark plugs comprising a frame having a pair of spaced opposed jaws; one of said jaws having means defining a support whereby a spark plug can be adjustably held with its electrodes extending towards the opposite jaw; means slidably mounted in the said opposite jaw for movement towards and away from the spark plug; feelers carried by said slidably means for insertion into the gap between the central and outer electrodes of the spark plug, said feelers being mounted for relative movement with respect to said slidable means; at least two opposed movable jaws carried by said first jaw and operable to exert equal and opposed forces against the outer electrodes of the spark plug whereby the outer electrodes may be pressed towards the central electrode; wedge means operable to exert equal forces on said movable jaws; a push rod supported by the aforesaid opposite jaw and operable to actuate said wedge; a yoke connecting said push rod to said slidable means for movement therewith; and means journaled in the aforesaid opposite jaw for moving said sliding means.

8. A device for adjusting the gap in spark plugs comprising a frame having a pair of spaced opposed jaws; the first of said jaws having a support whereby a spark plug can be adjustably held with its electrodes extending towards the opposite jaw; slidable means mounted in said opposite jaw for reciprocative motion towards and away from the spark plug; a grapping head carried by said slidable means and axially movable with respect thereto; feelers carried by said gapping head for insertion into the gap between the central and outer electrodes of the spark plug; at

least two rams carried by said gapping head and movable with respect thereto, said rams being operable to move towards each other and to bend the outer electrodes of the spark plug towards the feelers which are thereby clamped between the central and outer electrodes; movable jaws pivotally carried by said first jaw, there being one movable jaw for each of said rams and each movable jaw having one end portion thereof engaging one of said rams to move said rams toward the spark plug electrodes; wedge means operable to exert equal forces on said movable jaws; a push rod supported by the said opposite jaw and operable to actuate said wedge; a yoke connecting said push rod to said slidable means for movement therewith; means journaled in said opposite jaw for moving said sliding means; and an operating handle for rotating said journaled means.

9. The device described in claim 8 wherein spring means are provided between said opposite jaw and said slidable means to oppose the movement of said slidable means toward the spark plug; spring means provided between said slid-
able means and said gapping head to oppose the movement of said gapping head with respect to said slidable means; and spring means provided between said movable jaws and rams, whereby movement of said slidable means will cause said gapping head and said rams to move in succession toward said spark plug.

10. The device described in claim 8 wherein movement of the operating handle in one direction moves said feelers towards and into the gap between the electrodes, and movement of the operating handle in the other direction moves said feelers away from the spark plug and pulls them out of the spark plug gaps, and a stop plate mounted on said frame to hold the spark plug while the feelers are being withdrawn from the gap.

11. The device described in claim 8 wherein said feelers are of substantial length and of flexible material whereby they can be temporarily flexed to conform to the gap spaces during adjusting operation and withdrawal from the gap spaces without disturbing the gap setting.

12. The device described in claim 8 wherein said gapping head is provided with means to hold said feelers in various positions whereby the positions of said feelers can be accommodated so as to fit spark plugs of various dimensions.

13. The device described in claim 8 wherein stop means mounted on the first of said jaws are provided to limit the movement of the gapping head towards the spark plug whereby the gapping head remains stationary after said feelers have been inserted into the gaps, and while said rams are moving to bend the outer spark plug electrodes towards the central electrode.

14. The device described in claim 8 wherein at least one adaptor ring is provided to properly locate the spark plug on the said first jaw with respect to said feelers and said rams, said adaptor ring being of such dimensions as to allow free shifting of the spark plug in a plane at right angles to its central electrode.

15. The device described in claim 8 wherein two rams are carried by said gapping head, said rams being coaxial and lying in a plane at right angles to the axis of the spark plug electrode as it is held on said support.

16. The device described in claim 8 wherein two rams are carried by said gapping head, the axes of said rams lying in a plane containing the axis of the central electrode of the spark plug,

and their axes intersecting the axis of the spark plug central electrode at equal angles, said angles being other than ninety degrees.

17. A device for adjusting the gap in spark plugs comprising feelers mounted on said device and adapted for insertion between the center and outer electrodes of a spark plug; means mounted on said device operable to cause the insertion of said feelers within the gaps and to simultaneously press the outer electrodes towards the center electrode with said feelers inserted therebetween.

18. A method of adjusting the gap in spark plugs having a central insulated electrode and annularly spaced ground electrodes; inserting at least two equiangular spaced feelers between the central and ground electrodes, then simultaneously pressing the ground electrodes towards the center electrode with the feelers inserted therebetween, the forces exerted against the center electrode forming a closed force diagram without the imposition of any bending moment upon the central electrode.

19. In a machine adapted for gapping spark plugs, an adapter applicable for locating a spark plug in the center of and in definite relation in height to operative parts of the machine, and a gapping mechanism facing the electrodes of a located spark plug and comprising a movable head and a movable guide member operatively connected to said head, means adapted to move said head and said member in a direction toward and from the electrodes of the spark plug, spacer elements on said guide member, insertable between the center and outer electrodes during said member's movement toward the spark plug, and means adapted to force the outer electrodes against said inserted spacer elements under a pressure exerted by said head sufficient to produce a permanent gap between the center and outer electrodes of a size substantially that of the thickness of said spacer elements.

20. In a machine of the character described, an adapter applicable for locating a spark plug in the center of and in definite relation in height to operative parts of the machine, and a gapping mechanism facing the electrodes of a located spark plug and comprising a movable head and a movable guide member operatively connected to said head, means adapted to move said head and said member in a direction toward and from the electrodes of the spark plug, spacer elements on said guide member insertable between the center and outer electrodes during said member's movement toward the spark plug, means adapted to limit the movement of said guide member in relation to the height of the spark plug's electrodes and further means capable to force the outer electrodes against said inserted spacer elements under a pressure exerted by said head sufficient to produce a permanent gap between the inner and outer electrodes of a size substantially that of the thickness of said spacer elements.

21. A device for adjusting the gaps in spark plugs comprising at least two equiangularly spaced feelers mounted on said device and adapted to be inserted between the central and outer electrodes of a spark plug; means operable to simultaneously press the outer electrodes toward the central electrode with said feelers clamped therebetween, the forces exerted by said means against the central electrode forming a closed force diagram without the imposition of any bending moment upon the central electrode;

13

and actuating means on said device operable to first insert said feelers into the gaps and then to actuate first named means.

22. A device for adjusting the gaps in spark plugs comprising at least two equiangularly spaced feelers mounted on said device and adapted to be inserted in the gaps between the central and outer electrodes of a spark plug; first means operable to insert said feelers into the gaps between said electrodes; second means operable to simultaneously press the outer electrodes toward the central electrode until said feelers are clamped therebetween, the forces exerted by said second means against the central electrode forming a closed force diagram without the imposition of any bending moment upon the central electrode; and actuating means on said device to first operate said first means and after the insertion of said feelers in the gaps to operate

5

14

said second means, said actuating means including a wedge member for driving said second means.
